ANIMATED TOY

Edmond Le Blanc, Montreal, Quebec, Canada

Application December 17, 1942, Serial No. 469,283

2 Claims. (Cl. 46—42)

The present invention pertains to an animated toy operating automatically after having been set in motion and giving the appearance of being operated by figures of human beings.

The motive power is derived from balls rolling down a series of chutes. At the final chute, the ball actuates linkage which in turn operates a selective release and stop means for delivering one ball at a time from the uppermost chute. Parts of the apparatus are attached to light weight, articulated figures to present the illusion mentioned above.

The invention is fully disclosed by way of example in the following description and in the accompanying drawing in which:

Figure 1 is a perspective view of the device;

Figure 2 is a detail vertical section;

Figure 3 is another detail vertical section; and

Figure 4 is a detail plan view.

Reference to these views will now be made by use of like characters which are employed to designate corresponding parts throughout.

The framework of the toy includes a flat base 1 from which extend a pair of uprights 2. Across the upper ends of the uprights are laid a pair of rails 3, parallel to each other and horizontal. Vertical bars 4 are secured to the rails at one end and support one end of a chute 5. A pair of opposed fork members 6 are mounted on the rails, and the lower end of the chute is suspended from these members by springs 7.

Beneath the lower end of the chute 5, the uprights 2 support a sloping chute 8 having an opening 9 in its lower end. Beneath this end is another chute 10 having an opening 11 in its lower end. Beneath this end, in turn, is a sloping platform 12 extending from one of the uprights 2.

The opposite upright has journaled therein a drum 13 on a horizontal axis. Radial vanes 14 divide the drum into radial pockets 15. Across the axis of the drum is balanced a beam 16 carrying a receptacle 17 adjacent to the platform 12. A lateral extension 18 from the base carries an articulated figure 19 having arms 20 pivoted to the remaining end of the beam 16.

A link 21 is hinged at 22 to the drum 13 and extends upwardly. The upper end is hinged at 23 to a lever 24 fulcrumed at 25, as shown more clearly in Figure 2. The lever terminates at the lower end of chute 5 and carries a downwardly extending stop 26 near the extremity. In the full-line position, the stop holds a row of balls 27 from rolling off the chute. As the link 21 is raised to move the lever to the dotted-line posi-

tion, the stop permits the first ball to roll off the chute, while the extremity of the lever engages and retains the next ball.

Hingedly suspended from a rod 28 across the rails 3, a flap 29 lies over the chute 8 to be swung by a ball rolling down the latter. The flap is attached to an articulate figure 30, imparting an animated motion thereto. To the upper structure is fixed the figure 31 of a man having the appearance of directing the proceedings.

The link 21 has an upward extension 21' which carries the figure 32 of a rooster in an aggressive position and constructed of a flexible material in sheet form. The figure has a movable wing 33. The head of the figure is joined by a string 34 to a rearward fixed portion 35 of the frame structure. The wing 33 is suspended from a string 36 extending upwardly over the upper edge of the figure 32 and downwardly to a point of attachment to one of the rails 3, as shown in Figure 3.

In the operation of the device, motion may be initiated by manually pressing the receptacle 17 downward. The link 21 is thus shifted upward, and the figure 19 is moved as if operating the apparatus. The link tilts the lever 24 to release the first ball 27 as previously described. This ball drops to the chute 8, then to chute 10, platform 12 and receptacle 17 to repeat the movement of beam 16 and the cycle initiated thereby. Thereafter these cycles occur automatically until the supply of balls is exhausted.

The upward shift of link 21 and extension 21' raises the body of the figure 32 against the string 36, thereby causing the wing 33 to flap. The head, however, is held nearly stationary by the string 34, so that the figure has the appearance of a fighting cock.

Although a specific embodiment of the invention has been illustrated and described, it will be understood that various alterations in the details of construction may be made without departing from the scope of the invention as indicated by the appended claims.

What I claim as my invention is:

1. An animated toy comprising a frame structure, a series of intercommunicating chutes supported thereby and sloping downwardly from each other in downward succession, a balanced beam journaled in said structure and having one end beneath the lower end of the lowest chute, a receptacle on said end of said beam and adapted to receive a member rolling off the lowest chute, a selective release and stop member at the lower end of the uppermost chute, and a link connecting said beam to said stop member and adapted

to operate said stop member, a flexible animal figure carried by said link, strings connecting parts of said figure to said structure, whereby motion of the link imparts movement to the said figure.

2. An animated toy comprising a frame structure, a series of intercommunicating chutes supported thereby and sloping downwardly from each other in downward succession, a balanced beam journaled in said structure and having one end beneath the lower end of the lowest chute, a receptacle on said end of said beam and adapted

5 to receive a member rolling off the lowest chute, a selective release and stop member at the lower end of the uppermost chute, a link connecting said beam to said stop member and adapted to operate said stop member, and an articulated figure carried by said structure and hinged to the remaining end of said beam, a flexible animal figure carried by said link, strings connecting parts of said figure to said structure, whereby motion of the link imparts movement to the said figure.

10 EDMOND LE BLANC.
